UNITED STATES PATENT OFFICE.

GEORGE FETTERS, OF CANTON, OHIO.

SMOKE-CONSUMER.

1,083,075.

Specification of Letters Patent. Patented Dec. 30, 1913.

Application filed October 15, 1912. Serial No. 725,911.

To all whom it may concern:

Be it known that I, GEORGE FETTERS, a citizen of the United States, residing at Canton, in the county of Stark and State of 5 Ohio, have invented new and useful Improvements in Smoke-Consumers, of which the following is a specification.

This invention has relation to means whereby the gases and other products 10 evolved during the combustion of coal may be consumed, thereby utilizing a maximum percentage of the heat units and economizing in the consumption of fuel.

The invention provides a novel form of 15 sprayer for delivering air in regulated quantity to the combustion chamber, said sprayer embodying independent passages, the one for air and the other for steam, the air passage having regulable air inlets whereby 20 the amount of air to be supplied in a given time may be controlled, said air being heated in its passage to prevent injury to the furnace or boiler which would be liable to occur by the delivery of cold air into the furnace.

25 nace.

The invention consists of the novel features, details of construction and combination of parts, which hereinafter will be more particularly set forth, illustrated in the accompanying drawing, and pointed out in the appended claims.

Referring to the drawing, forming a part 35 of the specification, Figure 1 is a sectional view, showing the application of the invention. Fig. 2 is a sectional view on the line x-x of Fig. 1. Fig. 3 is a section on the line y-y of Fig. 1.

Corresponding and like parts are referred 40 to in the following description, and indicated in all the views of the drawing, by the same reference characters.

The invention comprises a body 1 in which is formed a chamber 2, a passage 3 and a recess 4, the latter opening through a side of 45 the body and having an opening 5 at its inner end leading into the chamber 2. One end of the body 1 has a flange 6 by means of which the body is secured to a wall or other part of the furnace. The opposite 50 end of the body is formed with a recess 7 and is externally screw-threaded. The recess 4 is adapted to be connected with a source of supply of steam by means of a pipe 8, which is provided in its length with a 55 valve. A cap 9 is fitted to the threaded end of the body 1 and its rim 10 is formed

with a plurality of openings 11, which constitute air inlets. The inner wall of the rim 10 is threaded to match the screw-threads upon the outer end of the body 1. When 60 the cap is in position and screwed upon the body 1 to the limit of its inward movement the air openings 11 are entirely closed. By backing or unscrewing the cap 9 the air openings 11 may be uncovered more or less 65 to regulate the quantity of air to be supplied to the furnace in a given time according to existing conditions to insure a perfect combustion of the smoke and gases. The edge of the cap 9 is notched and is engaged by 70 means of a spring 12, which holds the cap in the adjusted position. One end of the spring 12 is secured to the body 1 and its opposite end projects to be engaged by the hand so as to release the cap when it is required to turn 75 the same to regulate the effective size of the air inlets. An opening 13 formed in the flanged end of the body 1 communicates with the chamber 2. The openings 5 and 13 are in line with each other and communicate 80 with the chamber 2.

A pipe 14 is secured at one end within the opening 5 and extends through the opening 13 and is provided at its other end with a spray nozzle 15 for delivering the steam 85 into the combustion chamber of the furnace in minute jets. A pipe 16 is secured at one end within the opening 13 and incloses the pipe 14 and is provided at its opposite end with a flared nozzle 17, which incloses the 90 spray nozzle 15. The flared nozzle 17 is set into the wall 18 of the furnace and projects some distance beyond the spray nozzle 15. The manner of construction and attaching the flared nozzle 17 to the furnace wall 18 95 is unimportant within the purview of the invention.

It is to be understood that the device may be applied to either wall of the furnace according to location and the make of the 100 furnace. When the invention is in operation steam is supplied to the pipe 8 and entering the recess 4 passes into the pipe 14, thence to the nozzle 15 and is delivered into the combustion chamber in minute jets, creating a suction within the flared nozzle 17, thereby drawing air through the inlets 11 into the recess 7, passage 3 and pipe 16. The air in its travel through the pipe 16 is heated by means of the steam passing through 105 the pipe 14 and commingles with the steam in the nozzle 17, thereby entering the com- 110

bustion chamber in a heated state so as to prevent any possible injury to the furnace or boiler. The amount of air may be regulated by adjustment of the cap 9 in the manner stated.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention what is claimed as new, is:—

1. In a device of the character specified a body having end spaces in communication by means of a side passage and formed with an inner hollow extension with which a fluid medium supply pipe connects, means for supplying air in regulated quantity to one

end of the body, a pipe connected with the opposite end of the body and communicating with the space thereof, and a second pipe 30 passing through the first mentioned pipe and spaced therefrom and connected with the hollow extension of the body.

2. In a device of the character specified a hollow body provided with an inner hollow 35 extension projecting from a side thereof forming end spaces and a side passage connecting the end spaces, a pipe connected with the hollow extension to supply a fluid medium thereto, a cap threaded to one end 40 of the hollow body and adapted to regulate the supply of air therethrough, a pipe connected with the opposite end of the body and in communication with the space thereof, and a second pipe passing through the 45 first mentioned pipe and spaced therefrom and connected with the hollow extension.

In testimony whereof I affix my signature in presence of two witnesses.

GEORGE FETTERS.
